DESIGN FOR A SHOE

George K. Guinzburg, Chappaqua, N. Y., assignor to I. B. Kleinert Rubber Company, New York, N. Y.

Application February 12, 1941, Serial No. 98,965

Term of patent 7 years

To all whom it may concern:

Be it known that I, George K. Guinzburg, a citizen of the United States of America, residing at Chappaqua, county of Westchester, and State of New York, have invented a new, original, and ornamental Design for a Shoe, of which the following is a specification, reference being had to the accompanying drawing, forming a part thereof.

Fig. 1 is a side view of a shoe showing my new design.

Fig. 2 is a top view thereof.

Fig. 3 is an enlarged fragmentary view of a portion of one of the cross straps of the shoe.

I claim:

The ornamental design for a shoe, as shown.

GEO. K. GUINZBURG.
